UNITED STATES PATENT OFFICE.

WILLIAM J. SWEENEY, OF SOUTH CHICAGO, ILLINOIS.

COVER FOR SLIDING-POLE HOLES.

1,069,740.

Specification of Letters Patent. Patented Aug. 12, 1913.

Application filed August 28, 1912. Serial No. 717,481.

To all whom it may concern:

Be it known that I, WILLIAM J. SWEENEY, citizen of the United States, residing at South Chicago, in the county of Cook and State of Illinois, have invented certain new and useful Improvements in Covers for Sliding-Pole Holes; and I do hereby declare the following to be a full, clear, and exact description of the invention, such as will enable others skilled in the art to which it appertains to make and use the same.

This invention has for its object to provide covers for the descent holes in the floors of the sleeping quarters of firemen in fire department buildings and means for automatically raising the same when necessary to permit descent therethrough whereby accident may be avoided.

The invention consists in the features of construction and combinations of parts hereinafter fully described and particularly claimed.

In the accompanying drawings illustrating suitable embodiments of the invention: Figure —1— is a perspective view partly in section of a cover and means for automatically raising the same constructed in accordance with my invention. Fig. —2— is a detail view in elevation of a trip latch employed.

In all fire department houses openings are provided in the floors of the sleeping rooms through which the firemen may descend to the lower apparatus-containing floor on vertical poles extending centrally through said openings. The descent is thereby greatly accelerated but the said openings are a source of constant danger to the firemen and numerous accidents due to firemen falling through the same result from the fact that they are entirely unprotected at all times.

The object of my invention is, therefore, to provide covers for the said holes which are normally retained over the same but which, when an alarm is sounded, may be tripped by the man on watch so that the firemen may readily descend therethrough when required.

The invention may be carried out in various ways, two of which I have illustrated in

the accompanying drawings and which I will now proceed to describe.

As shown in Fig. —1— the cover 1 is provided with a descent hole through which the slideable pole 2 passes centrally and vertically. This pole usually consists of a polished brass tube. The said cover 1 is of somewhat greater diameter than the opening or hole which it is intended to cover and is provided centrally with a sleeve 3 through which the pole 2 passes. Said sleeve is preferably secured to the cover by means of the flange 4 thereof in a well-known manner.

Disposed within the pole or tube 2 is a counterweight 5 which is heavier than said cover 1 and is connected with the latter by means of the chains or cords 6, each of these flexible members 6 being secured at one end to the said cover 1 or flange 4 and trained over pulleys 8 rotatably mounted in a suitable manner upon the bracket 9 in the outer end portion of which the upper end of the tube or pole 2 is secured, said bracket being secured to the wall or post 10 contiguous to said opening. Normally the weight 5 maintains the cover raised to a position in which the upper edge of the sleeve 3 contacts with the lower face of the bracket 9. Secured at one end to said counterweight 5 is a cable auxiliary flexible member 11 which is trained over pulleys 12 and 13 secured to the ceiling and said wall or post 10 or other convenient support. The said cable is provided between its ends with a member 14 consisting of a rectangular strip of metal or the like having a longitudinal slot 15 therein in which the end portion of the sliding bolt 16 of a latch 17 is adapted to engage. Pivotedly mounted on the wall or post 10 at its elbow portion is a bell crank lever 18 having the free end of one of its arms connected by means of a link 19 with one end of said sliding bolt 16, the other arm of said lever 18 being connected with one end of a chain or cord 20 which is suitably passed over pulleys not shown and having its other end disposed contiguous to the telephone or alarm box and within reach of the night watchman. A spring 21 normally maintains said lever 18 at the limit of its movement whereby the sliding bolt 16 is

100

held at the forward limit of its movement. A pin 22 disposed in the path of the arm of said lever 18 connecting with said sliding bolt 16 serves to limit the rearward movement of the latter.

The cord 11 normally supports the counterweight 5 at the upper limit of its movement or at least aids the weight of the cover in overbalancing the counterweight thus 10 permitting the cover 1 to rest along its peripheral edge portion upon the floor surrounding the descent hole. By tripping the sliding bolt 16 to release the same from engagement in the slot 15 of the member 14 15 the counterweight will be released and being of greater weight than said cover 1 will obviously immediately raise the latter to the upper limit of its movement. In order that the cover 1 may not rotate, the same is provided with a bifurcated projection 23 between the arms of which a cord 24 is engaged, the latter being vertically disposed and connected at one end with the bracket 9 and at its other end with the floor and constituting a vertical guide for said projection 23. After the latch 16 has been tripped to release the member 14 from engagement therewith the cover may be again lowered by drawing up the weight 5 by means of the 25 cord 11 as will be obvious.

While the foregoing is the preferred form of embodiment of the invention, the same may also be carried out as illustrated in Figs. —3— and —4— in which the cover 25 is hinged to the floor by means of the hinges 26. The said cover is provided with a radial slot 27 which is normally maintained closed by means of two gates 28 which are hinged to the respective side edges of said slot 27. 30 Each of these gates is provided on its lower face with a substantially semi-cylindrical projection 29 and each is further provided in its outer edge with a recess 30 forming an opening through which the chains 31 pass, 35 the latter being each connected at one end to the lower face of the cover 25 contiguous to said slot 27 and on respectively opposite sides of the latter, said chains passing underneath the said projections 29 of said gates 40 28. The said flexible members 31 are secured at their other ends to one end of a cord or cable 32. The latter passes through an opening 33 in the bracket 34 to which the upper end of the pole 2 is secured and 45 is trained over pulleys 35 and 36 rotatably mounted on said bracket and at its other end is secured to the counterweight 37 vertically movable within said pole 2. The said pole 2 passes between said chains 31, as shown, 50 so that when the cover is thrown up its outer end will pass back of the pole 2 and leave the entire descent opening free. Attached 55 at one end to said counterweight 37 is a cord

or cable 38 trained over pulleys 39 and 40 rotatably mounted on said bracket 34 and 60 which carries the member 41 similar to the member 14 and which is similarly provided with a slot in which a latch plunger 16 engages. The latter is connected with one arm of the bell-crank lever 42 pivotally secured at its elbow to the wall back of the descent opening and having its other arm connected with the chain 43 by means of which it is manually operated. The spring 44 normally holds said lever 42 in position 70 to maintain the plunger 16 at the forward limit of its movement and a pin 45 limits the movement of said lever 42 in a direction to withdraw the plunger 16 from engagement in the slot in said member 41. The said 75 lever 42 is operated by the man on watch similarly to the lever 18 and upon being so operated to withdraw the plunger 16 from engagement with the member 41 the counterweight 37 will obviously descend. Such 80 descent movement will result first in opening the gates 28 so as to leave the slot 27 free for the passage of the pole 2 therethrough as the cover 25 moves pivotally from a horizontal to a vertical position.

Preferably means are provided for holding the cover 25 in its raised position, said means comprising the shaft 45 rotatably mounted in suitable bearings secured to the wall and which carries two dogs 46, the nose 95 portions of which are rounded and are disposed in the path of the outer edge portion of said cover 25 which when coming in contact therewith serve to raise said dogs. The latter are provided with recesses 47 in which 100 said end portion of the cover 25 is adapted to be received and held against return movement in a well-known manner. Rigidly secured to said shaft 45 at one end is a bell crank lever 48, one arm of which is normally 105 maintained in contact with the wall to limit the movement of said shaft in one direction by means of the helical tension spring 49 secured at one end to said wall and at its other end to the other arm of said lever 48. 110

It will be noted that the construction last described is somewhat more complex and expensive than that shown in Fig. —1— but is also efficient and serves the purpose.

I claim as my invention:

The combination with a hollow descent pole passing through an opening in a floor and having its upper open end exposed, of a cover for said hole adapted to rest on the floor around the same and slidably mounted on the pole, a pair of cables each secured at one end to said cover at diametrically opposite points contiguous to the middle thereof, a bracket engaged with the upper end of the pole and secured to a wall of the building, pulleys mounted on said bracket on

diametrically opposite sides of the pole and over which said cables are trained, a counterweight heavier than said cover disposed within the pole and suspended from the 5 other ends of said cables, a cable secured at one end to said weight, pulleys over which said last-named cable is trained, and trip mechanism disposed on the wall contiguous to the opening for engaging said last-named 10 cable to support said weight at an elevation

to maintain the cover at the lower limit of its movement.

In testimony whereof I have signed my name in presence of two subscribing witnesses.

WILLIAM J. SWEENEY.
